UNITED STATES PATENT OFFICE.

ELY W. SINTOW, OF BROOKLYN, NEW YORK, ASSIGNOR TO ART CAGE MFG. CO., INC.,
OF NEW YORK, N. Y., A CORPORATION OF NEW YORK.

DESIGN FOR A BIRD CAGE.

Application filed May 31, 1927. Serial No. 22,238. Term of patent 14 years.

To all whom it may concern:

Be it known that I, ELY W. SINTOW, a citizen of the United States, residing at the city of New York, borough of Brooklyn, county of Kings, and State of New York, have invented a new, original, and ornamental Design for a Bird Cage, of which the following is a specification, reference being had to the accompanying drawing, forming part thereof.

The figure is a perspective view of a bird cage, embodying my new design.

I claim:

The ornamental design for a bird cage, as shown.

ELY W. SINTOW.
